US0D1082862S

(12) **United States Design Patent** (10) Patent No.: **US D1,082,862 S**
(45) Date of Patent: ** Jul. 8, 2025

(54) **GAS COMPRESSOR**

(71) Applicant: **Atlas Copco (India) Ltd.**, Maharashtra (IN)

(72) Inventors: **Sanket Vinayak Lathkar**, Maharashtra (IN); **Rajshekhar Shivannappa Dandin**, Maharashtra (IN); **Manoj Dilip Purohit**, Maharashtra (IN); **Bikkani Tharun Chowdary**, Maharashtra (IN)

(73) Assignee: **Atlas Copco Airpower, Naamloze Venootschap**, Wilrijk (BE)

(**) Term: **15 Years**

(21) Appl. No.: **29/891,669**

(22) Filed: **May 9, 2023**

(30) **Foreign Application Priority Data**

CLAIM

The ornamental design for a gas compressor as shown and described.

DESCRIPTION

FIG. 1 is a perspective view of a gas compressor, showing our new design.

FIG. 2 is a front view thereof.

FIG. 3 is a rear view thereof.

FIG. 4 is a left side view thereof.

FIG. 5 is a right side view thereof.

FIG. 6 is a bottom view thereof; and,

FIG. 7 is a top view thereof.

The broken lines depict portions of the gas compressor that form no part of the claimed design.

1 Claim, 7 Drawing Sheets
